US00D711891S

(12) **United States Design Patent**
Emami et al.

(10) **Patent No.:** US D711,891 S
(45) **Date of Patent:** ** Aug. 26, 2014

(54) **DATA ACCESSING DEVICE**

(71) Applicant: **Kingston Digital, Inc.**, Fountain Valley, CA (US)

(72) Inventors: **Arman Emami**, Fountain Valley, CA (US); **Yi-Ting Lin**, Hsinchu (TW); **Hsi-Ming Tsai**, Hsinchu (TW); **Peter Leekuo Chou**, Fountain Valley, CA (US)

(73) Assignee: **Kingston Digital, Inc.**, Fountain Valley, CA (US)

(**) Term: **14 Years**

(21) Appl. No.: **29/457,976**

(22) Filed: **Jun. 14, 2013**

(51) LOC (10) Cl. **14-02**

(52) U.S. Cl.

USPC **D14/480.5**

(58) **Field of Classification Search**

USPC D14/411, 433, 435.1, 436, 480.1–480.7, D14/484.1, 137, 155, 203.1–203.8, 240, D14/242; D13/133, 154

(57) **CLAIM**

We claim the ornamental design for a data accessing device, as shown and described.

DESCRIPTION

FIG. 1 is a perspective view of a data accessing device showing the claimed design;

FIG. 2 is a front elevational view thereof;

FIG. 3 is a rear elevational view thereof;

FIG. 4 is a left side elevational thereof;

FIG. 5 is a right side elevational thereof;

FIG. 6 is a top plan view thereof;

FIG. 7 is a bottom plan view thereof; and,

FIG. 8 is a perspective view showing the data accessing device in a usage state.

The broken lines are directed to environment and are provided for illustrative purpose only; the broken lines form no part of the claimed design.

1 Claim, 5 Drawing Sheets
